US00D577748S

(12) **United States Design Patent**
Tingen et al.

(10) **Patent No.:** **US D577,748 S**
(45) **Date of Patent:** **** Sep. 30, 2008**

(54) **BLOCKER FOR EYEGLASS LENSES**

D381,343 S * 7/1997 Elie D15/124

(75) Inventors: **Tory L. Tingen**, Gordonsville, VA (US);
Sally C. Kocotas, Charlottesville, VA (US); **Darryl Scott Evans**, Winchester, VA (US); **Bruce Seymour Ferris**, Richmond, VA (US); **Sean Derek Anderson**, Powhatan, VA (US)

* cited by examiner

Primary Examiner—Antoine D Davis

(74) *Attorney, Agent, or Firm*—Berenato, White & Stavish

(73) Assignee: **National Optronics, Inc.**,
Charlottesville, VA (US)

(57) **CLAIM**

The ornamental design for a blocker for eyeglass lenses, as shown and described.

(**) Term: **14 Years**

DESCRIPTION

(21) Appl. No.: **29/287,926**

(22) Filed: **Oct. 2, 2007**

(51) **LOC (8) Cl.** **15-09**

FIG. 1 is a rear elevational view of our design;

(52) **U.S. Cl.** **D15/125**

FIG. 2 is a rear perspective view;

(58) **Field of Classification Search** D10/46;
D15/124-125; 33/286; 356/399; 451/42,
451/384, 390

FIG. 3 is a front elevational view;

See application file for complete search history.

FIG. 4 is a front perspective view;

FIG. 5 is a left side elevational view;

FIG. 6 is a right side elevational view; and,

FIG. 7 is a top plan view.
